UNITED STATES PATENT OFFICE.

HERBERT L. MATHERS, OF TAMAQUA, PENNSYLVANIA, ASSIGNOR TO ATLAS POWDER COMPANY, OF WILMINGTON, DELAWARE, A CORPORATION OF DELAWARE.

OIL-SWITCH FOR HIGH-TENSION ELECTRIC CURRENTS.

1,277,981.

Specification of Letters Patent.

Patented Sept. 3, 1918.

Application filed September 21, 1917. Serial No. 192,590.

To all whom it may concern:

Be it known that I, HERBERT L. MATHERS, a citizen of the United States, residing at Tamaqua, in the county of Schuylkill and State of Pennsylvania, have invented certain new and useful Improvements in Oil-Switches for High-Tension Electric Currents, of which the following is a specification.

10 This invention relates to oil switches for high tension electric currents and the object of the invention is to provide a very simple and economical oil switch so constructed that it may be used to complete electric circuits carrying high tension currents without danger of arcing and without danger of the operator being shocked while manipulating the switch.

Switches have heretofore been provided 20 in which the moving contact points were immersed in an oil bath to prevent the formation of an arc, or the production of sparks at the moment of making or breaking the circuit. However, these switches have been 25 quite complicated and consequently expensive to manufacture. It is primarily the object of the present invention to secure the desired results, namely, the provision of a switch which may be safely used in localities where arcing would prove dangerous, as for example in buildings where explosives are manufactured or where explosive vapors may be present; while at the same time the structure by which these results 30 are secured will comprise few, simple and inexpensive parts.

Further objects and advantages of the invention will be set forth in the detailed description which now follows.

40 In the accompanying drawings:—

Figure 1 is a face view of the switch;

Fig. 2 is an elevation of the inside face of the cover of the switch, and the parts carried thereby;

45 Fig. 3 is a face view of the switch with the cover and the parts carried thereby removed;

Fig. 4 is a vertical sectional view; and

50 Fig. 5 is a detail sectional view through a pointer carried by the operating shaft.

Like numerals designate corresponding parts in all of the figures of the drawings.

Referring to the drawings, 5 designates a box or casing having a lining 6 of sheet lead which makes the same oil tight. A

cover 7 may be held in place in any desired manner, as for example by screws 8, as illustrated in Fig. 4 or by straps 9, as indicated in Fig. 1. In the latter case the straps will be provided with locks 10 to prevent unauthorized persons from removing the cover. The bottom of the receptacle receives a slate plate 11 and the top 7 carries a slate plate 12. The slate plate 12 supports a plurality of, in the present instance, three, U-shaped resilient contacts 13, that are secured to plate 12 by countersunk screws 14. The plate 11 carries a corresponding number of U-shaped spring contacts 15 that are secured to said plate 11 by countersunk screws 16. 60 Journaled in the plates 11 and 12 and in the cover 7 is an operating shaft 17 that carries an operating knob or other suitable type of handle, 18. The shaft 17 has secured thereto for rotation therewith a disk 70 19 of insulating material and this disk carries a plurality of copper buttons 20, there being as many of said buttons as there are pairs of contacts 13 and 15 respectively.

When, by a partial rotation of shaft 17, 80 the several copper buttons are caused to move between the members of the pairs of contacts 13 and 15, a circuit will be completed between these contacts. Suitable contacting wires, indicated at 21, lead from the contacts 13, and suitable contacting wires 22 lead from the contacts 15. It is to be understood that when in use the casing is filled with oil to such a point that the several contacts are submerged in the oil so 85 that when the buttons 20 move between the contacts 13 and 15, arcing or the formation of sparks, is positively prevented. Furthermore, the immersion of the contact points and the buttons in oil prevents corrosion thereof and keeps these parts clean and in condition to make a highly effective contact.

Furthermore, it is to be noted that when moving into contacting position a rubbing 90 action between the buttons and the resilient contacts 13 and 15 takes place. This further tends to insure an efficient contact between these parts. In order that the operator may be able to determine what position the switch occupies, the shaft 17 is provided with a pointer 23 and with indicating matter 24, 25 and 26 with which the pointer 23 co-acts. This pointer is provided with a tongue 27 on its under face which is adapted 100 105 110

to snap into a recess 28 of one or the other of a plurality of spring detents 29, 29.

While the drawings show three sets of contact points, it is to be understood that the number may be varied at will, it being manifestly well within the range of the obvious to vary the number of contacts to suit the particular conditions at any given time.

10 While the elements shown and described are well adapted to serve the purposes for which they are intended it is to be understood that the invention is not limited to the precise construction set forth but that

15 it includes within its purview such changes as fairly come within the spirit of the appended claims.

Having described the invention, what I claim is:—

20 1. The combination with an oil tight casing, of a shaft mounted to rotate therein, a disk of insulating material carried by said shaft, metallic buttons carried by said disk of insulating material and projecting therethrough, blocks of insulating material disposed upon opposite sides of said disk and lying in substantial parallelism therewith, contact members of resilient material and of U-shape, one of the legs of said contact members being secured to the corresponding block of insulating material and the other and free legs of said contact members being disposed in the path of move-

ment of the buttons of the insulating disk, an indicating pointer carried by the shaft 35 and located outside of the casing, and a detent acting to stop the same in that position where the buttons of the insulating disk lie directly between and establishes communication between the opposed contact members. 40

2. A device of the character described comprising a box-like oil tight casing, blocks of insulating material secured therein and lying in spaced relation to each other, a shaft mounted to turn in said blocks of 45 insulating material, a disk of insulating material carried by and turning with said shaft, a plurality of contact buttons carried by said disk and projecting therethrough and beyond the opposite side thereof, a 50 plurality of contact members secured to each of the blocks of insulating material, said contact members being of U-shape and being formed of resilient material and comprising free legs which lie in the path of 55 movement of the contact buttons, an indicating pointer carried by said shaft outside of the casing and spaced detents for engaging said pointer and holding the same in the contact making position of the buttons. 60

In testimony whereof I affix my signature in the presence of two witnesses.

HERBERT L. MATHERS.
